[57] CLAIM

The ornamental design for a typewriter, as shown and described.

DESCRIPTION

FIG. 1 is a front, top and right side perspective view of a typewriter, showing our new design, with the platen cover pivoted to raised position and the detachable paper sheet guide in place;

FIG. 2 is a rear, bottom and left side perspective view thereof;

FIG. 3 is a front, top and right side perspective view thereof in closed position;

FIG. 4 is a rear, bottom and left side perspective view thereof with the paper guide support in raised position and with the paper guide detached therefrom.
